UNITED STATES PATENT OFFICE.

ALBERT F. STERNBERG, OF CHICAGO, ILLINOIS.

DESIGN FOR A CLUTCH MEMBER.

SPECIFICATION forming part of Design No. 31,897, dated November 28, 1899.

Application filed November 1, 1899. Serial No. 735,542. Term of patent 7 years.

To all whom it may concern:

Be it known that I, ALBERT F. STERNBERG, a citizen of the United States, residing at Chicago, in the county of Cook and State of Illinois, have invented and produced a certain new and original Design for Clutch Members; and I do declare the following to be a full, clear, and exact description of the invention, such as will enable others skilled in the art 10 to which it appertains to make and use the same.

The invention relates to a new and original design for clutch members; and it consists of a design of the configuration shown in the 15 accompanying drawings, in which—

Figure 1 is a perspective view of the clutch member. Fig. 2 is a longitudinal sectional view.

The leading feature of the design comprises the body portion 1, having near its lower end 20 and in its opposite side recesses 2 and a central aperture 3. The upper end of the body portion has a perforated head 4 and a laterally-projecting stud 5.

What I claim is—

25 The design for a clutch member, as herein shown and described.

In testimony whereof I have hereunto set my hand in presence of two subscribing witnesses.

ALBERT F. STERNBERG.

Witnesses:

DANIEL SEVAN,
BURTON J. ASHBY.
